UNITED STATES PATENT OFFICE.

WILLIAM E. DEPP, OF BROOKVILLE, PENNSYLVANIA.

CHURN-DASHER.

SPECIFICATION forming part of Letters Patent No. 352,610, dated November 16, 1886.

Application filed August 26, 1886. Serial No. 211,925. (No model.)

To all whom it may concern:

Be it known that I, WILLIAM E. DEPP, a citizen of the United States, residing at Brookville, in the county of Jefferson and State of Pennsylvania, have invented a new and useful Improvement in Churn-Dashers, of which the following is a specification.

My invention relates to improvements in churn-dashers; and it consists of the peculiar combination and novel construction and arrangement of the various parts for service, substantially as hereinafter fully described, and particularly pointed out in the claim.

The object of my invention is to provide an improved churn-dasher which will violently and thoroughly agitate the cream, and thereby accomplish the operation of churning in a very short time, and to provide a dasher which shall possess superior advantages over all others that have preceded it in points of simplicity and durability of construction, ease of operation, and cheapness of manufacture.

In the accompanying drawings, Figure 1 is a side elevation of a churn-dasher embodying my invention, showing it in proper position in a churn, with the latter in section. Fig. 2 is a horizontal sectional view on the line *x x* of Fig. 1. Fig. 3 is a detached perspective view of one of the inclined dasher-blades with the revolving wheel thereon.

Referring to the drawings, in which like letters of reference denote corresponding parts in all the figures, A designates the vertical dasher-staff, which is arranged centrally within a suitable vessel and supported therein, and this staff is rotated in a vertical plane by any suitable driving-gear; but as this driving mechanism does not form a part of my present improvements I have not deemed it necessary to further refer to the same, or illustrate it more fully in this specification.

B designates the dasher-blades, which are permanently secured to the vertical staff and project outwardly therefrom. These dasher-blades extend from opposite sides of the vertical dasher-staff, and in an inclined position with relation thereto, the blades being inclined downwardly and outwardly from the staff, and having their lower ends projecting beyond the vertical faces of the staff, and their inner ends secured to the staff at the sides of the latter, as clearly shown.

C designates the revolving wheels, which are carried at the lower free extremities of the inclined dasher-blades B, one of these wheels being provided for each of the inclined dasher-blades. These agitator-wheels consist of a central hub, *c*, and a series of inclined wings, *c'*, which are arranged diagonally to each other and equidistant apart, so that the cream will strike the wings during the rotation of the dasher through the cream, and thereby revolve the agitator-wheel, as will be very readily understood. This agitator-wheel has a shaft or pin, *d*, passing through a suitable opening, *e*, in the central hub thereof, and this pin is rigidly affixed to the inclined dasher-blade B. The agitator-wheels are arranged on one of the sides of the inclined dasher-blades and at the outer end thereof, and the wings of the agitator-wheel are inclined at a greater angle than the inclination of the dasher-blade, and so arranged with relation thereto that the front edge of the said wing clears the end of the blade B in advance of the rear edge of the wing, whereby the cream that is deflected from the upper inclined surface of the blade B will strike the radial diagonal wings of the agitator-wheel, and thus increase the speed of the said wheel, which is rotated by the wings passing through the cream during the rotation of the dasher.

This being the construction of my improved churn-dasher, the operation thereof is as follows: The dasher is rotated by the driving mechanism, in the direction indicated by the arrow in Fig. 2, and the inclined blades B first strike the cream and agitate the same to a considerable degree. The diagonal blades or wings of the agitator-wheel are acted upon by the cream during the rotation of the dasher, so that the wheel is rotated to increase the agitation in the cream, and the speed of the agitator-wheel is accelerated or increased by the upward current of cream generated by the revolving inclined blade B, the cream being deflected from the upper surface of the downwardly-inclined blade and impinging with considerable force upon the diagonal blades of the agitator-wheel.

Although I have only shown and described my improved dasher as being provided with eight of the downwardly-inclined blades B, and the loosely-journaled agitator-wheels car-

ried on the outer extremities of the blades, still I would have it understood that I hold myself at liberty to increase and vary the number of blades and the agitator-wheels therefor, 5 as may be deemed desirable or be found to give the best results in practice.

I do not desire to broadly claim the combination of a vertical dasher-staff carrying horizontal arms to which are loosely connected 10 vertical wheels, as I am aware that such a device is not new; but I confine myself to the combination with an inclined dasher-blade rotating with the vertical shaft, and the agitator-wheel loosely journaled on the outer end 15 of the said inclined blade and having its radial wings set at an angle to the blade, whereby the current of cream that is deflected from the said blade will act upon the wings of the agitator-wheel and thereby accelerate the speed 20 thereof.

It will be observed that the wheels in my churn are arranged parallel with and on one side of the blades B at the lowest point thereof, with the wings of the wheels extended above the 25 blades. Inasmuch as the edge of the blades strikes the cream first, the cream will be deflected down the blades, (by reason of the downward inclination given to the blades,) and, striking the wings C' C' of the wheels, will cause the 30 latter to revolve. By this arrangement there is little or no resistance offered by the wheels against the body of the cream, since the blades will cut through the latter, and the wheels are so disposed as to be readily rotated by the cream-

currents descending the blades, and yet offering little resistance to the rotation of the dasher. 35

It will also be observed that the several blades B are disposed in different horizontal planes, so that the wheels will not interfere with each other in their action on the body of the cream. 40

My improved churn-dasher is very simple and strong of construction, cheap and inexpensive of manufacture, and thoroughly efficient and reliable in operation, the dasher creating a very violent agitation among the 45 particles of the cream, and thereby facilitating the operation of churning.

Having thus fully described my invention, what I claim as new, and desire to secure by Letters Patent, is—

A churn-dasher comprising the rotary shaft A and the downwardly-inclined blades B, affixed to and extending outward from the staff, the wheels C, loosely journaled directly to one side of and parallel with the blades at the lowest point thereof, and wings C', provided on the wheels and extended above the blades, whereby the blades will cut through the cream, and the currents descending or deflected down the blades will strike the wings of the wheels, 55 as set forth.

In testimony that I claim the foregoing as my own I have hereto affixed my signature in presence of two witnesses.

WILLIAM E. DEPP.
